UNITED STATES PATENT OFFICE.

LEE H. KAUPKE, OF ROCK ISLAND, ILLINOIS, ASSIGNOR TO ROCK ISLAND PLOW COMPANY, OF ROCK ISLAND, ILLINOIS, A CORPORATION OF ILLINOIS.

DISK HARROW.

1,399,018.

Specification of Letters Patent.

Patented Dec. 6, 1921.

Application filed July 29, 1918. Serial No. 247,119.

To all whom it may concern:

Be it known that I, LEE H. KAUPKE, a citizen of the United States of America, and resident of Rock Island, Rock Island county, Illinois, have invented a certain new and useful Improvement in Disk Harrows, of which the following is a specification.

My invention relates to an improvement in disk-harrows, and particularly to that type wherein two complete harrows are arranged in tandem relation.

The objects of my invention are to provide an improved construction for thus connecting the sets of disk gangs in tandem relationship, and to otherwise generally improve the construction and arrangement of parts whereby a more efficient structure will be obtained.

My invention is particularly adapted for use in connection with tractor-drawn implements, although it is not limited to such type of implement.

In the accompanying drawings, I have illustrated one specific embodiment of my invention in which—

Figure 1 is a plan view of a harrow embodying the features of my invention.

Fig. 2 is a side elevation.

Fig. 3 is a detail sectional view on the line 3—3 of Fig. 2, looking in the direction of the arrows.

Fig. 4 is an enlarged detail view of the forward end of the harrow.

Fig. 5 is a detail sectional view taken on the line 5—5 of Fig. 4.

Fig. 6 is a partial plan view of the parts shown in Fig. 4.

I have illustrated two disk-harrows arranged in tandem relationship. The rear harrow comprises two disk gangs 11 and 12, carried by a pair of transverse bars 13, 13^a, in the usual and well-known manner. These two sets of disk gangs 11 and 12 are pivotally mounted on a frame which consists of the transverse frame bar 15 and a pair of forwardly extending frame bars 16, 17, which, as clearly shown in Fig. 2, extend first upwardly and then downward on a slight incline, thereby forming an arch-shaped structure. These two frame bars 16, 17, converge toward one another, and at their forward ends are secured together by means of the transverse strap 18. To the center of this strap 18 there is connected a casting 19, which is provided with a flat

horizontal ear 20 for securing said casting to the transverse strap, and at its forward end is provided with a flat vertically extending ear 21. Pivots mounted on this casting, on the pin 22, there are a pair of forwardly extending draft arms 23, which are adapted to be held in various angular positions by means of the pin 24 which engages with any one of a series of holes 25 in the ear 21. With this arrangement, it will be seen that these two draft arms can be held rigidly in any one of a plurality of angular positions, whereby the elevation of the front ends of these draft arms may be varied. The front ends of these draft arms are adapted to be connected to a suitable clevis 26, which is usually connected to the rear of a tractor, or some other source of draft power. By means of the adjustability of the arms 23, they are adapted to be connected with clevises of varying heights.

The casting 21 is provided with a vertical bearing for the king pin 27, which king pin is held rigidly within such casting by means of the pin 28. This king pin extends downwardly below the casting 19, and forms a vertical pivotal bearing for the casting 29. This casting carries a horizontal pivot, consisting of the pin 29^a, for the two parallel straps 30, which at their rear ends are secured to the forward end of two angle bars 30^a which form part of the frame for the forward harrow, and which extend rearwardly, being connected at their rear ends to the transverse member 31. Secured to the opposite ends of this transverse member is a frame member consisting of the arch-shaped bar 32, as shown in Fig. 1, thus forming with the transverse member 31 a triangular-shaped draft frame for the forward disk harrow.

This forward disk harrow likewise consists of two disk gangs 33, 34, carried by the transverse bars 35, 36. These disk gangs are pivotally connected to the outer ends of the transverse frame bar 31 by means of the straps 37, which extend between the transverse bars 35, 36 and the frame bars, and the downwardly extending straps 38 which are connected to the axis of the disk gangs and form a pivotal support for the same.

In order to provide means for varying the angling position of the various disk gangs, I provide hand levers located at the forward end of the implement and within easy reach of an operator on the tractor. To angle the

disks of the forward harrow, I provide a hand lever 39 which is pivotally mounted on the cross member 40 carried by the arch-shaped member 41, which in turn is mounted 5 on the angle bars 30⁴. The lower end of this hand lever is pivotally connected to two rearwardly extending arms 42, one of which is connected to the inner end of the gang 33, and the other of which is connected to the 10 inner end of the gang 34. The arch member 41 is provided with a series of rack teeth and the hand lever is provided with the usual spring tooth, whereby the hand lever can be held in any adjusted position. It will be 15 readily seen that by movement of the hand lever in a forward and back direction that the angling position of the disk gangs of the forward harrow can be varied, as desired.

In order to adjust the rear disks, I provide 20 two hand levers 43, one mounted near the forward end of each of the frame bars 16 and 17. As each of these hand levers control the angling of one of the rear disks in a similar manner, a description of one will 25 suffice for both.

A rearwardly extending arm 44 is connected to the hand lever 43, and at its rear end this arm is connected to a second downwardly and rearwardly extending arm 45, 30 which in turn is connected to the inner end of the rear disk gang. The pivotal bearing for the bars 44, 45, is carried by a swinging link 46, which is pivoted at its opposite end to a rearwardly extending bar 47 secured at 35 its rear end to the transverse frame bar 15. The forward end of this bar 47 is connected to a transverse brace bar 48 which extends between the two frame bars 16, 17. In order to provide a more firm pivotal mounting be- 40 tween the bars 44, 45, and link 46, I provide an offset strap 49, carried by the bar 45, and connected to the pivotal point so as to hold the members 44 and link 46 between this offset strap and the bar 45. With this construc- 45 tion, it will be seen that through proper movement of the hand lever 43, the rear disk gang can be suitably angled and the hand lever is adapted to be held in any ad- justed position by means of the series of rack 50 teeth 50 which is engaged by the usual spring tooth 51 carried on the hand lever 43.

In order to provide a suitable downward pressure on the disk gangs, I have mounted 55 on each of the front disk gangs the usual weight pans 52, and likewise on the rear harrow I provide suitable weight pans 53 supported by the brackets 54 secured to the transverse frame bar 15. These brackets support these weight pans somewhat to the 60 rear of the center line of the disks, and in this manner the weight exerted by these pans operates through sufficient leverage to counter-balance the weight of the long forwardly extending frame of the rear harrow, thus en- 65 abling a more effective pressure to be ex-

erted upon these rear disks. In order to apply a further downward pressure to the front disks, I have also provided a yoke 55, as clearly shown in Fig. 3, which is adjustably supported on the transverse frame bar 70 31. The transverse portion of this yoke is adapted to bear downward on the two links 42, and by adjusting the vertical position of this yoke 55 by means of the pin and hole connection between this link and the trans- 75 verse frame bar 31, the pressure exerted by this yoke on the rods 42 can be readily ad- justed and thus the pressure which is ex- 80 ereted on the inner end of the disk gangs will be likewise adjusted.

It will thus be seen that I have provided a very efficient form of tandem disk harrow, and one in which the rear harrow swings freely about the point of draft connection between the harrow and the tractor, while 85 the front harrow freely pivots about an axis carried by the rear harrow, and in such relationship with the front pivotal connection that the disk gangs can be swung freely without danger of any interference between 90 the disks of the front and rear harrows. I furthermore provide means for independently adjusting the angling position of the front and rear disk gangs, which means are in such position as to be readily accessible to 95 the operator on the tractor.

While I have illustrated and described one specific embodiment of my invention, it will be understood that I do not wish to be lim- 100 ited to the exact construction shown and de- scribed, but that various changes and modi- fication may be made without departing from my invention.

What I claim as my invention is:

1. In an implement of the class described, 105 a rear harrow and a front harrow arranged in tandem relationship, each of said harrows consisting of two sets of disk gangs, a frame for said rear harrow extending forwardly and over said front harrow, a member se- 110 cured to the front end of said frame, a pair of draft arms carried by said member ex- tending forwardly thereof, and a bearing socket in said member carrying a king pin, a second member pivotally mounted on said 115 king pin, and a frame for said forward harrow pivotally connected to said second mem- ber.

2. In an implement of the class described, 120 a pair of disk harrows arranged in tandem relationship, a frame for the rear harrow extending forwardly and over the front har- row, and means for mounting said harrows so that they are free to swing vertically in- 125 dependently of each other and are also free to swing laterally independently of each other about an axis located in substantially the center line of draft.

3. In an implement of the class described, 130 a pair of disk harrows arranged in tandem

relationship, a frame for said rear harrow extending forwardly and over the front harrow, a mounting for said rear harrow at the front end of said frame, whereby said rear harrow is free to swing laterally and vertically, and a mounting for the front harrow carried by said frame and permitting the front harrow to swing laterally and vertically independently of the rear harrow.

4. In an implement of the class described, a pair of disk harrows arranged in tandem relationship, a suitable frame for said rear harrow extending forwardly and over the front harrow, connections for angling the disks of the rear harrow, said connections comprising a rearwardly extending jointed arm, and a swinging link carried by said frame for supporting the joint of said arm.

5. In an implement of the class described, a pair of disk harrows arranged in tandem relationship, a suitable frame for said rear harrow extending forwardly and over the front harrow, connections for angling the disks of the rear harrow, said connections comprising an arm connected to the disk gangs and extending forwardly, a second arm pivotally connected to the forward end of said first mentioned arm, a hand-lever pivotally connected to the forward end of said second arm, and operative to reciprocate said arms, and a swinging link carried by the frame and supporting the pivotal connection between said arms.

6. In an implement of the class described front and rear harrows provided with disk gangs arranged in tandem relationship, a frame for said front harrow, a frame for said rear harrow extending forwardly over said front frame, said frames being pivotally connected together, a pair of hand-levers mounted at the forward end of said rear frame, in front of the disk gangs of the front harrow, connections therefrom to said rear disk harrow for angling the same, an independent hand-lever mounted at the forward end of said front harrow frame, and connections therefrom to said front harrow disks for angling the same.

7. In an implement of the class described, front and rear harrows arranged in tandem relationship and each provided with a pair of oppositely disposed disk gangs, a frame for the front harrow, a frame for the rear harrow extending over said front frame, said frames being pivotally connected together, a pair of hand-levers mounted at the forward end of said rear frame in front of the disk gangs of the front harrow, connections from said hand-levers to said rear disks for independently angling said disk gangs, a single hand-lever mounted at the forward end of said front harrow frame, and connections therefrom to each of said front disk gangs for simultaneously angling said front disk gangs.
